CLAIM

The ornamental design for a portable test instrument, substantially as shown and described.

DESCRIPTION

FIG. 1 is a front perspective view of the portable test instrument;

FIG. 2 is a back perspective view thereof;

FIG. 3 is a top view thereof;

FIG. 4 is a bottom view thereof;

FIG. 5 is a left side view thereof;

FIG. 6 is a back view thereof; and,

FIG. 7 is a front view thereof.

The broken lines shown in the figures are for the purpose of illustrating the environmental structure and form no part of the claimed design. The unevenly-spaced broken line at the front end and visible in FIGS. 2-5 illustrate the boundary of the claimed design and form no part thereof.

The right side of the portable test instrument is a mirror image of the left side of the portable test instrument depicted in FIG. 5.

(Continued)

The shade lines in the figures show contour and not surface
ornamentation.
